CLAIM

The ornamental design for an endless conveyor belt, as shown and described.

DESCRIPTION

1. Endless conveyor belt

1.1 : Perspective

1.2 : Perspective

1.3 : Top

1.4 : Bottom

1.5 : Left

1.6 : Right

1.7 : Front

1.8 : Back

The edges shown with dashed and dash-dotted lines are not part of the claimed design, as the conveyor belt is endless; reproductions 1.7 and 1.8 are cross-sectional views in which the hatched area represents the cut area.
